UNITED STATES PATENT OFFICE.

HAROLD EDWARD NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR AN ARTICLE OF HOLLOW WARE.

56,938.

Specification for Design.

Patented Jan. 18, 1921.

Application filed July 19, 1920. Serial No. 397,510. Term of patent 7 years.

To all whom it may concern:

Be it known that I, HAROLD EDWARD NOCK, a citizen of the United States, residing at Newburyport, in the county of Essex and State of Massachusetts, have invented a new, original, and ornamental Design for an Article of Hollow Ware, of which the following is a specification, reference being had to the accompanying drawing, forming a part thereof.

The figure is a plan view of a circular plate showing my new design applied to a section of the border thereof.

The design comprises an ornamental decoration having the configurations and charac-

teristics delineated, and, as shown, is embodied in a circular plate through application to its border, but it is contemplated that the design may, in like manner, also be embodied in or applied to various other articles of hollow ware having different configuration and shapes.

The motif comprising the enlarged medallion is repeated at desired intervals around the border of the article.

I claim:

The design for an article of hollow ware ornamented substantially as shown and described.

HAROLD EDWARD NOCK.
